UNITED STATES PATENT OFFICE.

ALFRED REINSCH, OF BERLIN-MARIENFELDE, GERMANY, ASSIGNOR TO DAIMLER-MOTOREN-GESELLSCHAFT, OF UNTERTURKHEIM, GERMANY, A FIRM.

ARRANGEMENT OF THE OPERATING CAMS OF THE FUEL VALVES IN DIESEL MOTORS.

Application filed April 20, 1922. Serial No. 555,661.

To all whom it may concern:

Be it known that I, ALFRED REINSCH, a subject of the State of Bavaria, Germany, residing at Berlin-Marienfelde, Prussia, 5 Germany, 11 Hranitzkystrasse, have invented certain new and useful Improvements in the Arrangement of the Operating Cams of the Fuel Valves in Diesel Motors, of which the following is a specification.

10 In the construction of Diesel-motors the fuel feed valves are usually arranged in the plane of the center axis of the cylinders, so that the two fuel feed valves of a cylinder block have a rather great distance from 15 each other. The operating cams for the fuel feed valves are disposed on the operating shaft in the same planes, in which the fuel valves are arranged and accordingly also have a rather great distance from 20 each other. On account of this construction it is necessary to provide separate arrangements for the adjustment of the needle stroke of the fuel feed valves.

According to the invention the before described construction is simplified thereby, 25 that the operating cams for the two fuel feed valves of a cylinder block are arranged closely abreast of each other on the operating shaft between the vertical planes of 30 said valves. On account of this arrangement it is possible to employ a common needle stroke adjusting device for both valves whereby a saving of space and weight is obtained.

35 In the drawing, which represents one form of construction of the present invention,

Fig. 1 shows diagrammatically a front view of a Diesel-motor equipped with the 40 improved arrangement.

Fig. 2 is a plan view and

Fig. 3 is a side view of the same.

The two fuel feed valves are disposed as 45 usually in the planes of the center axis of the cylinders. The appropriate operating cams a' and b' however are not disposed in the manner usual until now, on the operating shaft below said fuel valves, but are arranged on this shaft c between the 50 vertical planes of said fuel feed valves a

and b in close proximity to each other. The transmission of the stroke of said cams to the fuel feed valves is effected by means of rod and lever arrangement d, f, g .

Having thus particularly described the 55 nature of my invention, what I claim as new and desire to secure by Letters Patent of the United States is:

1. In an internal combustion engine of the Diesel type, the combination of a plurality of upright cylinders, fuel feed valves for said cylinders located in registry with the vertical axes thereof and in line with each other, a horizontal cam-shaft extending parallel to the plane passing through the axes of the cylinders, operating cams on said shaft in close proximity to each other between the parallel vertical planes which pass through the axes of the cylinders and are perpendicular to the cam-shaft 70 and transmission means whereby said cams are operatively connected with said valves. 65

2. In an internal combustion engine of the Diesel type, the combination of a plurality of upright cylinders, fuel feed valves 75 for said cylinders located in registry with the vertical axes thereof and in line with each other, a horizontal cam-shaft extending parallel to the plane passing through the axes of the cylinders, operating cams 80 on said shaft in close proximity to each other between the parallel vertical planes which pass through the axes of the cylinders and are perpendicular to the cam-shaft, vertical rods in registry with said cams and 85 adapted to be operated thereby, bell-crank levers pivotally connected with said rods and cranks journaled on said engine between said valves and extending toward each other, said cranks having one member 90 in registry with one member of each bell-crank and the other connected with one of said valves whereby the latter are operated by said cams. 95

In testimony whereof I affix my signature in presence of two witnesses.

ALFRED REINSCH.
